MEANS FOR FASTENING GELATINIZED BANDS

Kenneth M. Henderson, Winnetka, Ill., assignor to Ditto, Incorporated, Chicago, Ill., a corporation of West Virginia

Application February 11, 1932, Serial No. 592,329

1 Claim. (Cl. 24—33)

The present invention relates to fastening devices and more in particular to fastening devices adapted to provide a flexible joint between two adjacent pieces of material, as for example, the ends of gelatinized bands commonly employed in hectograph machines.

Among the objects of the present invention is to provide a novel fastening device by which the ends of pieces of material may be readily and effectively secured together to provide a continuous strip of material and in which a flexible joint therebetween is provided.

The present invention further contemplates the idea of providing a novel fastening means for securing adjacent ends of material together and includes a piece of material provided with openings adapted to be folded along the medial line thereof to provide an edge formed with alternately arranged and spaced projecting portions adapted to be disposed in intermeshing relation with a similar piece of material associated with the end of another piece of material. The openings formed by the folds of these projecting portions are adapted to be disposed in alignment when the projecting portions are in intermeshing relation, whereby suitable means, such as a removable key, may be received therethrough for securing these pieces of material together and to provide for a flexible joint, the folded pieces of material being adapted to be readily and easily secured in any desired manner to some flexible material, such as the adjacent ends of gelatinized bands or the like, as employed in hectograph machines.

Still another object within the purview of the present invention is to provide a novel fastening device for securing the ends of pieces of material together wherein a removable key is provided, this key being of such a construction as to prevent accidental displacement or removal thereof when the same is in place for holding the ends of these pieces together.

Other objects, features, capabilities and advantages are comprehended by the invention, as will later appear and as are inherently possessed thereby.

Referring to the drawing:

Figure 1 is a top plan view of adjacent pieces of material secured together to provide a flexible joint in accordance with the present invention;

Figure 2 is a fragmentary top plan view similar to Figure 1 of the drawing, disclosing the parts in spaced relation;

Figure 3 is a fragmentary view in cross section

taken in a plane represented by line 3—3 of Figure 1 of the drawings;

Figure 4 is a fragmentary top plan view similar to Figure 1 of the drawing disclosing adjacent pieces of material secured together by means of a modified key member; and

Figure 5 is a plan view of the modified key member shown in Figure 4 of the drawing.

Referring now more in detail to the drawing, an embodiment of the present invention is disclosed in association with strips or bands of flexible material 2 and 4, such as the gelatinized bands employed in hectograph machines. In the present disclosure, each of these bands 2 and 4 may be wound upon spindles 6 which may be formed with hubs 8 terminating in the projecting stubs 10 adapted for insertion in journaling means which may be provided in the side frames of a hectograph machine, or the like. When these bands 2 and 4 are used as shown, and as for example in a hectograph machine, the same are adapted to pass over a platen or any other desired surface of the hectograph machine, and the same may be unwound from one spindle onto another, the present invention being concerned primarily with suitable fastening means whereby two adjacent pieces of gelatinized bands, such as 2 and 4, may be readily and conveniently secured together.

In the present embodiment, each of the pieces of material 2 and 4 has secured to its ends or edges another piece of material 12. Each of these pieces of material is of similar construction and is formed with a plurality of spaced openings and is folded along the medial line thereof to provide a castellated-like edge formed with a plurality of spaced projecting portions 14. These pieces of material 12 are folded over the ends of the strips or bands 2 and 4 and may be secured thereto in any desired manner, as for example, by the stitching 16, or the like. These pieces of material 12 are further stitched along the line 18 to provide a looped or folded edge 20 having a transverse opening 22 therethrough.

As clearly shown in the drawing, the projecting portions 14 of each of the pieces of material 12 are formed in opposite relation to the openings of the oppositely disposed piece of material so that when the ends of the bands or strips 2 and 4 are brought into adjacent relation the projecting portions 14 of the strips 12 will be in intermeshing relation one with the other. When in this intermeshing relation, the openings 22 formed by the folds of the pieces of material 12 are in aligned relation in a trans-

verse direction and are adapted to receive a removable key member 24 which is adapted to be inserted through these aligned openings for retaining these projecting portions in their intermeshing relation. The key 24 is of somewhat flat construction and substantially rigid, and thus provides a flexible joint permitting relative angular movement between the ends of the strips 2 and 4 so that these strips may be conveniently rolled or unwound from a spindle or other similar element, such as the spindle 6.

In Figure 4 of the drawing is disclosed an alternative arrangement for securing adjacent ends of material together. In this figure, the adjacent ends of material 2 and 4 are provided with folded pieces of material 12 which are provided with openings and folded, as shown in Figure 3 of the drawing, to form a castellated-like edge provided with a plurality of spaced projecting portions 14. In this embodiment, however, these pieces of material 12 are secured together by a key member 24 which, as shown in Figure 5 of the drawing, is formed with a plurality of spaced recesses 26 which are adapted to receive the loops 20 of the projections 14. It will be readily apparent that when the key member 24 is inserted through the

transverse opening 22 formed by the loops 20, the engagement of these loops 20 in the recesses 26 will prevent accidental displacement or removal of this key member.

While I have herein described and upon the drawing shown an illustrative embodiment of the invention, it is to be understood that the invention is not limited thereto but may comprehend other constructions, arrangements of parts, details and features without departing from the spirit of the invention.

I claim:

A device for securing the ends of material together, comprising in combination, adjacent pieces of flexible material, a piece of flexible material secured to each of said first named pieces of material, said second named pieces of material having looped portions formed with spaced projecting portions adapted to be disposed in intermeshing relation, said projecting portions having openings adapted to be disposed in alignment when said portions are in intermeshing relation, and a removable key member insertable through said aligned opening to secure said pieces of material together and to provide a flexible joint.

KENNETH M. HENDERSON.
